UNITED STATES PATENT OFFICE.

RICHARD FLEMING, OF LYNN, MASSACHUSETTS, ASSIGNOR TO GENERAL ELECTRIC COMPANY, A CORPORATION OF NEW YORK.

REGULATION OF POLYPHASE FURNACES.

No. 904,194.

Specification of Letters Patent.

Patented Nov. 17, 1908.

Application filed February 13, 1908. Serial No. 415,768.

To all whom it may concern:

Be it known that I, RICHARD FLEMING, a citizen of the United States, residing at Lynn, in the county of Essex and State of Massachusetts, have invented certain new and useful Improvements in Regulation for a Polyphase Furnace, of which the following is a specification.

My invention relates to the operation of an electric furnace supplied with a polyphase alternating current, and comprises means for measuring the voltage between the electrodes and an inaccessible neutral point within the furnace, and thus provides a basis for the regulation of said electrodes.

When a star-connected polyphase current, for example, three-phase current, is supplied to an electric furnace, which may be either an arc or a resistance furnace, it is convenient to base the regulation of the electrodes upon the resistance between each electrode and a neutral point within the furnace. In the case of a resistance furnace, as an electrode is worn away, and its distance from the neutral point increases, the resistance offered to the current increases. When such a star-connected circuit is connected to a transformer delivering constant current, an unbalancing of the load by such change of resistance results in the unbalancing of the current in the system. In the case of an arc furnace it is convenient to maintain and regulate the length of the arcs by observing the drop in voltage from the electrodes to the bath.

An additional electrode has heretofore been placed within the furnace and connected by a metallic conductor to the common neutral of the transformer, either directly or through the earth. A voltmeter connected in shunt across the neutral interior electrode and any other electrode will indicate the voltage across the intervening path. As this interior electrode is subjected to the intense heat and the chemical activity of the charge, it is very troublesome, requiring frequent renewals.

By establishing an artificial neutral outside of the furnace, which will be a counterpart, or image, of the interior neutral point, I am able to dispense with the additional interior electrode.

My invention will best be understood by reference to the following description taken in connection with the accompanying drawing.

The novel features of my invention are pointed out with particularity in the appended claims.

The drawing shows diagrammatically a cross-section of the electric furnace 1, with electrodes 2, 3, 4 connected to a source of three-phase alternating current in mains 5, 6, 7, which are connected to some source of current with a star-winding, such as a transformer having an end of its coils connected to a common neutral point. The voltage is kept approximately constant with a suitable voltage regulator.

Although a three-phase circuit has been shown for illustration, it is obvious that any other polyphase circuit might have been shown. To each of the electrodes is connected a reactance coil; as coils 8, 9, 10, which are joined at a common point, 11. This point 11 then forms a neutral with reference to the three-phase current in the system. The current flowing through these reactances may be made as small as desired by increasing the number of turns. It will normally be equal in each coil, but suppose the resistance from the electrode 2, to the charge within the furnace were to increase, say, by wearing away of the electrode, an unbalancing of the load current would result. This unbalancing would result in increase of current flowing through the reactance coil 10, thus unbalancing the current in the reactances. This state of affairs would, of course, result in change of voltage across each coil. Therefore, by placing a voltmeter across each coil, as meters 12, 13, 14, a change of resistance for any cause whatever within the furnace would announce itself by a deflection of the voltmeters. In the case of an increase of resistance by a shortening of the electrode 2, as above described, an increase of voltage would result across the main 5 and neutral 11, thus causing a deflection of the voltmeter 14.

What I claim as new and desire to secure by Letters Patent of the United States, is,

1. The combination of a polyphase electric furnace, a source of alternating current, an

artificial neutral point, and means for measuring changes of potential between said artificial neutral and any of said electrodes.

2. The combination of a polyphase electric furnace, a source of alternating current of substantially constant voltage, reactances connected at one end to said electrodes and at the other end to a common neutral point,

and voltmeters in parallel with said reactances.

In witness whereof, I have hereunto set my hand this seventh day of February, 1908.

RICHARD FLEMING.
